UNITED STATES PATENT OFFICE.

GEORGE T. SWEETSER, OF BRONXVILLE, NEW YORK.

SOFT COLLAR.

Application filed August 1, 1927. Serial No. 209,790.

This invention is an improvement in fold or turn down collars, and more particularly in collars of the soft type, attached or detached.

5 In the usual construction of the soft, fold or turn down collar, the collar is held at the front by means of integral tabs at the end of the neck band or inner fold, the said tabs connecting with a collar button on the shirt.

10 There is nothing to hold the outer or display fold of the collar at the front, and the ends of said fold tend to spring away from the inner fold, thus presenting an unsightly appearance at the front of the collar.

15 It has been sought to remedy this condition by providing means on the outer fold of the collar, or in connection therewith, in the form of auxiliary tabs, having button holes for engaging the collar button, out-

20 side of the integral tabs at the ends of the neck band.

With this arrangement there are six laps of material on the collar button, namely, the two flaps of the shirt, and four tabs on the 25 collar. With the usual collar button, there is overcrowding of the shank, and it is somewhat difficult to button the last tabs, unless a collar button with a lengthened shank is provided, and such form of button is undesirable.

30 Attempts have also been made to remedy this condition, by providing loops on the outer fold, through which the usual button holed ends of the inner folds are passed, before being buttoned to the collar button.

Such a construction necessitates that the 35 loop be connected to the outer fold as close to the end as possible, in order that the button hole tabs may be withdrawn from the 40 loop when the collar is laundered. When the top of the loop is connected at the end of the collar, a portion of each loop will appear above the tie and cannot be hidden thereby.

45 If said upper connection is spaced away from the collar, the inner fold must be detached from the outer fold outside of the 50 loop connection, otherwise the tab cannot be inserted through the loop without crumpling of the collar. In addition with the arrangement specified, the tie must be threaded through the loops before it is connected with the collar.

55 One of the primary objects of the present invention is the provision of a form of collar, wherein a single attaching means is pro-

vided at each end of the collar for simultaneously connecting the two folds to the collar button, and wherein the said means is permanently connected with one fold of the 60 collar and detachably connected with the other fold, and is the sole connection of the collar end.

Another object is the provision of a collar of the character specified, in which the divergence from the usual construction and the usual appearance is as little as possible, while attaining the end sought in the close holding of the two folds at the front.

A further object is the provision of a construction of the character specified, wherein the cost of the collar is not increased to any material extent, and which may be laundered in the usual manner.

In the drawings forming a part hereof, Fig. 1 is a perspective view looking from above and the rear of an embodiment of the invention.

Fig. 2 is a plan view of the collar unfolded.

Fig. 3 is a section on the line 3—3 of Fig. 1.

Figs. 4, 5, 6 and 7 are plan views of parts of unfolded collars showing alternate arrangements.

Fig. 8 is a section on the line 8—8 of Fig. 7.

In the embodiment of the invention shown in Figs. 1, 2 and 3 inclusive, the improved collar, which is of the soft construction, comprises an inner fold or neck band portion 1, and an outer fold or display portion 2 connected in the usual manner. In the present instance, the inner fold 1 is provided at each end and on its inner face with a tab 3 of the same material as the collar, provided with one or more button holes 4, and connected to the band in such manner that the free end of the tab will extend beyond the end of the fold.

Referring to Fig. 2, it will be noted that the connected end of the tab is widened as shown at 5, to insure a firm anchorage of the tab to the fold, and the tab is so placed with respect to the band, that when the collar is folded and positioned around the neck of the wearer, the tabs at each end of the band will lap, so that both may be connected to the usual collar button, by engaging the button with one of the openings 4.

The outer fold 2 is provided near each end and on its inner face with a loop 6,

formed from a piece of material like that of the collar, and arranged with its long axis substantially perpendicular to the long axis of the tab, and in a position to register with the tab when the collar is folded.

The loops are so arranged that when the collar is folded the free end of the adjacent tab may be passed through the loop, as shown in Fig. 1, thus to connect the inner fold to the outer fold and to the collar button, by a single connecting means, that is, the tab. The folds may be multiply as shown in Fig. 3, or of any usual construction, and when multiply the loops and the tabs are connected with inner plies of the respective folds, so that no stitching appears upon the outer faces of the folds.

It will be noticed, referring especially to Fig. 2, that the integral tabs at the end of the neck band, which in the usual construction engage the collar button, are omitted in the present construction. The ends of the neck band or inner fold extend slightly beyond the ends of the outer fold, so that when the collar is in place the said ends, adjacent to the outer fold, lap slightly, as shown in Fig. 1. The said ends form what may be considered as tuck-in tabs, one tucking in behind the other, and the other tucking in between the first and the outer fold of the collar. They serve to close the gap between the ends of the inner fold.

In the Fig. 4 construction, the tabs 7, similar in all respects to the tabs 3, are connected with the ends of the inner fold 8, in the manner just described, and they are adapted to pass through loops 9 on the outer fold 10, thereby to provide a common connection for the two folds with the collar button. However, a portion 11 of the usual tab for connection with the collar button is left, to provide an additional lap at the ends of the inner fold or neck band. This tab portion 11 may be omitted, as in Fig. 1, or retained as in the remaining figures, as may be desired, but it has no function other than to provide a sufficient lap at the ends of the neck band.

In Fig. 5, the loop 12 is connected to the outer fold 13, and the inner fold 14 is provided with an eyelet or button hole 15, in a position such that when the collar is folded, the free end of the tab may be passed through the eyelet or button hole and connected with the collar button, thereby to provide a single means to connect both folds at each end to the collar button. The tab is like the tab 3, and similarly connected.

In Fig. 6, the tab 16 is connected to the outer fold 17, and the loop 18 is arranged on the inner fold 19. These parts or elements are so positioned that when the collar is folded, the tab may be passed through the loop, to provide a single connecting means for both folds at the end of the collar. In

Fig. 7 the tab 20 is connected with the inner fold 21 and the outer fold 22 is provided in the inner ply, with a pair of parallel, laterally spaced button holes 23, which provide between them a loop beneath which the free end of the tab may be passed.

In each construction the tabs and the loops are so connected to the folds, that no stitching appears on the display face of the collar, and in Fig. 7 the button holes are in the inner ply, so that they do not show on the outer or display face of the collar. In Fig. 5 the button hole is on the inner fold, so that it is hidden when the collar is in use. In none of the constructions does the collar, when in place, differ in appearance from the usual collar, except that a slight difference occurs at the connection of the tabs with the collar button. In use, however, this connection is hidden by the tie, so that the collar, outwardly, is precisely the same as the usual collar. The provision of two button holes in the tab, the button holes in alignment, enables a degree of adjustment in connecting the collar.

It will be apparent that in each construction a single means is provided for simultaneously connecting both folds of the collar to a collar button at each end of the collar, thus enabling the use of the ordinary collar button without any bulkiness at the connection of the collar therewith, and a collar is provided which may be laundered in the usual manner.

Were the usual holding tabs left in place, they would lap over the collar button, between the shirt and the attaching tabs. For this reason a portion or all of the usual tabs is omitted, so that there is no obstruction to the engagement of the attaching tabs with the collar button.

It will be apparent from the drawing and the description, that the improved collar has a single attaching means at each end of the same of a character such that both folds of the collar are connected to the button, and that the ends of the inner fold are so shaped as to lap above the collar button, while leaving the button itself exposed for the attachment of the tabs.

The ends of the neck band are imperforate, the neck band being provided with only one button hole for engaging the rear of the shirt. The single connecting tab at each end is positioned on the fold to which it is connected at its attached end, in spaced relation to the end of the fold, and is of a length to position the button hole with which it is provided beyond the end of the fold.

If desired, both ends of the neck band fold may be arranged as shown in Figs. 4, 5 and 6. That is they may have the relatively narrow integral tabs 11 to provide a lap of the inner fold above the collar button. One of the integral tabs may be omitted if

desired, the other providing sufficient lap, or both may be omitted, since the ends of the neck-band are shaped as shown in Fig. 1, to provide some lap above the collar button.

5 I claim:—

1. A turn down collar comprising a neck-band and an attached outer fold, one of said members having relatively narrow tabs at its opposite ends, each tab having a button hole, and means on the other member cooperating with each tab for connecting the said members, said tabs constituting the sole connecting means for attaching the ends of the collar to a collar button.
- 10 2. A collar having inner and outer folds, one of said folds having relatively narrow tabs at its opposite ends, each tab having a button hole, and means on the other fold cooperating with the adjacent tab for con-

necting said members together and to the 20 collar button, the ends of the neck band or inner fold being cut away in register with the button hole of the tabs to expose the collar button to enable direct connection of the tabs therewith when the collar is in place. 25

3. A collar having inner and outer folds, imperforate tuck in tabs at the ends of the inner fold, the inner fold also having openings adjacent the ends thereof, tabs secured to the outer fold near the ends thereof and 30 adapted to pass through said openings in the inner fold, and means on said latter tabs to secure the collar to the neck-band of a garment.

Signed at New York city in the county of 35
New York and State of New York this 28
day of July A. D., 1927.

GEORGE T. SWEETSER.
